UNITED STATES PATENT OFFICE

2,199,126

FOUNTAIN PEN

Feliciano Buschi, New York, N. Y., assignor to
 Unique Fountain Pen Corporation, New York,
 N. Y., a corporation of New York

Application July 6, 1938, Serial No. 217,689

4 Claims. (Cl. 120—47)

My invention relates to a novel form of self-filling fountain pen provided with a pumping arrangement in the cap of the pen, and providing large capacity for ink in the barrel of the pen.

5 Referring to the accompanying drawing, I have illustrated in Fig. 1 in longitudinal section a suitable form of pen embodying an application of my invention. Fig. 2 is a similar view of the pen in closed position.

10 3 indicates the barrel of the pen provided with the usual feed plug 4, pen point 5, and air tube 6 extending from the feed plug 4 through the center of the barrel as shown.

15 7 indicates a suitable form of rubber bag anchored at 8 in the internally and externally threaded nipple 9, secured in the end of the barrel 3 as shown, and 10 indicates a suitable form of valve which may be turned for controlling the passage of air into and out of the rubber bag 7. 20 11 indicates the cap of the pen which may be provided with the usual pocket clip 12, and this cap is preferably threaded as shown at 13 for engaging the threads 14 at the other end of the barrel when the pen is not in use. Within the outer end 25 of the cap 11 is secured a housing 15 for the pen 5 when not in use, and this housing has a vent 23 at the end and is surrounded by the tube or plunger 16, having a coiled spring 17 compressible between the top of the housing 15 and rotatable cap 18 when the plunger 16 is depressed by pressure upon the said cap 18, said cap having a circular flange 19 which is interrupted at points to allow the same to engage beneath a similarly interrupted flange 20 at the top of the ring 21 in 30 the top of the cap 11, so that when not in use, the plunger 16 may be depressed and the cap 18 may be turned to engage beneath the flange 20, thereby holding the same in closed position, the pen 5 passing within the housing 15 and being protected thereby.

40 In operation, after the cap 18 has been released by turning the same to clear the flange 20, the plunger 16 is projected outwardly until the circular flange 22 thereof strikes the filler ring 21 serving as a stop to limit the projection of the plunger 16. By now depressing the plunger, air within the housing 15 is forced beneath the valve 10 and into the collapsed bag 7, said bag having previously collapsed by the outward projection of the plunger 16. The expansion of the bag 7 now forces air down through the tube 6 and out beneath the pen 5. Upon releasing the plunger 16, the air in the expanded bag 7 is now exhausted and the bag 7 collapses, drawing ink

from a suitable well upwardly through the filler plug 4 into the barrel 3, and upon again depressing the plunger 16, the bag 7 again inflates, and air is again discharged through tube 6 beneath pen 5, and so on until the barrel 3 is substantially filled with ink. 5

A suitable cut or passage 24 may be provided to allow for the escape of air when applying the cap 11, and of course, various modifications may be made in the construction and arrangement of parts without departing from the spirit of the invention as claimed.

I claim:

1. A fountain pen with ink charging mechanism comprising a tubular body portion, means 15 for retaining the pen in one end thereof, a sac and valve therefor within the opposite end thereof, a removable cap adapted to be secured over said last mentioned end, a pen housing in said cap and a spring projected plunger pump operative 20 externally of said housing and from the end of said cap.

2. A fountain pen with ink charging mechanism comprising a tubular body portion, means 25 for retaining the pen in one end thereof, a sac and valve therefor within the opposite end thereof, a removable cap adapted to be secured over said last mentioned end, a pen housing in said cap and a spring projected plunger pump operative 30 externally of said housing and from the end of said cap, said spring concentric with said housing and cap and between the same.

3. A fountain pen with ink charging mechanism comprising a tubular body portion, means 35 for retaining the pen in one end thereof, a sac and valve therefor within the opposite end thereof, a removable cap adapted to be secured over said last mentioned end, a pen housing in said cap and a spring projected plunger pump operative 40 externally of said housing and from the end of said cap, said valve adapted to be closed when said pen is used, and to be opened when charging the same with ink.

4. A fountain pen with ink charging mechanism comprising a tubular body portion, means 45 for retaining the pen in one end thereof, a sac and valve therefor within the opposite end thereof, a removable cap adapted to be secured over said last mentioned end, a pen housing in said cap and a spring projected plunger pump operative 50 externally of said housing and from the end of said cap, and means for locking said pump within said cap when not in use.

FELICIANO BUSCHI,
